(57) **CLAIM**

The ornamental design for a wireless charger, as shown and described.

DESCRIPTION

FIG. 1 is a perspective view of a wireless charger showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof.

FIG. 9 is an enlarged detail view of area 9 shown in FIG. 1.

FIG. 10 is an enlarged detail view of area 10 shown in FIG. 2.

FIG. 11 is an enlarged detail view of area 11 shown in FIG. 3; and,

FIG. 12 is an enlarged detail view of area 12 shown in FIG. 6.

The broken lines in the drawings depict portions of the wireless charger that form no part of the claimed design. The broken lines encircling the enlarged views are for annotative purpose only and form no part of the claim thereof.

1 Claim, 12 Drawing Sheets
